CLAIM

The ornamental design for an aircraft with slotted inboard wings, as shown and described.

DESCRIPTION

FIG. 1 is a perspective view showing the top, left side and front of an aircraft with slotted inboard wings which forms a first embodiment of my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof;

FIG. 7 is a rear elevational view thereof;

FIG. 8 is a perspective view showing the top, left side and front of an aircraft with slotted inboard wings which forms an alternate embodiment of my new design;

FIG. 9 is a top plan view thereof;

FIG. 10 is a left side elevational view thereof;

FIG. 11 is a right side elevational view thereof;

FIG. 12 is a bottom plan view thereof;

FIG. 13 is a front elevational view thereof; and,

FIG. 14 is a rear elevational view thereof.

The broken line showing of portions of the aircraft with slotted inboard wings depicts environment and forms no part of the claim.
